[57] CLAIM

The ornamental design for a swing door for a glove
compartment of an automobile, as shown.

DESCRIPTION

FIG. 1 is a front elevational view of a swing door for a
glove compartment of an automobile, showing our new
design;

FIG. 2 is a rear perspective view thereof; and
FIG. 3 is a side perspective view thereof seen from the
right of FIG. 2.

FIG. 1

FIG. 2

FIG. 3
